(57) **CLAIM**

I claim the ornamental design for a weaving loom, as shown and described.

DESCRIPTION

FIG. 1 is a Perspective view of a weaving loom showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof;

FIG. 7 is a Bottom view thereof;

FIG. 8 is another Perspective view thereof with installed additional module as shown in FIG. 1; and,

FIG. 9 is another Perspective view thereof.

The broken lines are only for environmental purposes and form no part of the claimed design.

1 Claim, 9 Drawing Sheets
